STEAM LUBRICATOR

Filed July 7, 1930

UNITED STATES PATENT OFFICE

FRED LEE BADGETT, OF CHICKASKA, OKLAHOMA; BILLIE B. BADGETT ADMINISTRATRIX OF SAID FRED LEE BADGETT, DECEASED

STEAM LUBRICATOR

Application filed July 7, 1930. Serial No. 466,211.

This invention appertains to improvements in steam lubricators generally and more particularly to a type of the same adapted for use in connection with steam operated machinery, especially that class of machinery usually employed in exposed or inadequately protected places, such as in oil fields and the like.

The primary object of the invention is to provide an extremely simple and comparatively inexpensive mounting for a lubricator of the class set forth whereby the same may be quickly and easily installed in position on a heated part of an engine or the like in order that the efficiency of the lubricator will be maintained by the warmth transmitted to the same over long periods of use without constant care and attention or danger from stoppage during severe weather conditions.

Another object of the invention resides in the provision of a mounting which is so incorporated in the lubricator assembly and arranged to be attached to the heated part of an engine or the like that the heat from the latter will be transmitted directly to the lubricator parts thereby in addition to the latter being generally subjected to the heat radiated from the adjacent heated parts of the engine.

A further object of the invention is to provide a lubricator and mounting as hereinbefore characterized, wherein the parts of the lubricator will be assembled in closely spaced relation about a pipe section which is adapted to be coupled in on a usual steam supply pipe line in order that the lubricator parts will be subjected at all times to the heat radiated from the pipe section in addition to the warmth imparted thereto from the engine part on which it is mounted.

With the foregoing and other equally important objects and advantages in view, the invention resides in the certain new and useful combinations, construction and arrangement of parts, as will be hereinafter more fully described, set forth in the appended claims, and illustrated in the accompanying drawing in which:

50 Figure 1 is a vertical transverse section

through an engine manifold or the like and showing a practical embodiment of the mounting employed for supporting the steam lubricator thereon, the latter being in side elevation,

55 Figure 2 is an enlarged horizontal section taken on the line 2—2 of Figure 1, and

Figure 3 is a fragmentary elevation taken at right angles to Figure 1.

Referring to the drawing, wherein like characters of reference designate corresponding parts in the views thereof, the embodiment of the invention as shown therein by way of example only, is generally constituted in a steam lubricator of substantially unitary construction, consisting mainly of a lubricant container or reservoir 10 and a water reservoir or steam condenser 11 arranged in closely spaced relation one with respect to the other and joined together by a metal connection or web 13, and a mounting for supporting the lubricator in position on a steam pipe line or other heated part of the engine, as on the manifold *a* between the throttle valve *b* and the engine cylinders (not shown).

60 As shown, the lubricant container or reservoir 10 has its lower end portion provided with a plurality of depending leg portions 14 which are of metal and are preferably of 65 comparatively large cross-sectional area. The upper ends of these legs 14 are attached to the outer side wall of the container or reservoir 10, preferably in a permanent manner as by being welded thereto, while their lower ends project for a distance below the extreme lower end thereof and are screw threaded at their extremities for the reception on each of an upper lock nut 15 and a 70 lower lock nut 16, the latter being tightened in place after the corresponding openings in the supporting plate 17 have been engaged on the ends of the legs 14 below the upper nuts 75 15.

75 This supporting plate 17 is to be rested in horizontal position on a section of steam pipe or manifold *a*, and secured in that position by clamp bolts or the like 18. As shown, 80 these clamp bolts 18 are preferably U-shaped 85 100

and have their opposite extremities screw threaded to receive a lock nut 19 thereon after each bolt has been straddled beneath the pipe *a* and the ends thereof passed upwardly through complemental openings formed in the plate 17.

By making this plate 17 of metal, it acts to transmit heat from the pipe *a* directly to the legs 14 which, in turn, transmit it directly to the lubricant container or reservoir 10. It also acts to radiate a portion of the heat from its entire area, so that all parts of the lubricator assembly are more or less subject to the warmth therefrom.

15 The lubricator is braced in position by the steam pipe connections leading from the upper end of the reservoir or condenser 11 to the top side of the throttle valve *b*, which connections consist in a pipe section 19' between the reservoir or condenser 11 and one side of a control valve 20 and a pipe assembly 21 extending between the other side of said valve 20 and the upper end of a T 22. The adjacent ends of the T 22 and the pipe assembly 21 are preferably coupled together by a swedge nipple 23 and the opposite or lower end of the T to the top outlet of the throttle valve *b* by a straight nipple 24. Steam from the boilers (not shown) is lead to the side port of the T 22. The throttle valve *b* is bolted, as at 25, at its flanged side to a flange formed at the adjacent end of the steam pipe or manifold *a*.

30 The bottom of the water reservoir or steam condenser 11 is connected to the bottom of the lubricant container or reservoir 10 by a piped control valve 26 in order that water will pass there-through and below the lubricant in the container or reservoir 10 and thereby force the lubricant outwardly of the piped outlet 12 leading from the upper end of the latter. This outlet 12 conveys the lubricant to a sight feed device (not shown) and from thence the lubricant is ejected into the steam supply of the engine in the usual manner.

35 By having the lubricant container or reservoir 10 connected in closely spaced relation to the reservoir or condenser 11, by the metal member or support 13, heat from the steam passing through the manifold *a*, when the lubricator is mounted in position on the support 17, will be transmitted to the reservoir 11 directly through the member or support 13 from the container or reservoir 10. Also, additional heat will be imparted to both reservoir 10 and 11 by reason of the proximity thereto of the steam pipe connections between 40 the throttle valve *b* and the upper end of the water reservoir or condenser 11.

45 From the foregoing, it will be comprehended that the invention provides for the maintenance of the lubricant content of the container or reservoir 10 in a perfect fluid

state at all times and irrespective of extreme cold weather conditions, which is particularly desirable for steam lubricators generally and especially for those employed in the oil fields or in other exposed or badly protected places. Also, that water in the reservoir or condenser 11 will be prevented from freezing in order to be available for its intended use at all times. Consequently, the lubricator will be kept in the highest state of efficiency regardless of weather conditions and with but a minimum of care and attention.

50 The steam lubricator per se herein shown forms the subject-matter of my copending application filed on the 17th day of June, 1930, Serially Numbered 461,777, and, while it is not specifically described and claimed herein, it is to be construed to be a part of the present invention only in so far as its parts 55 present a true combination with the mounting structure.

55 Without further description, it is thought that the features and advantages of the invention will be readily apparent to those skilled in the art, and it will of course be understood that changes in form, proportion and minor details of construction may be resorted to, without departing from the spirit of the invention or its scope as claimed.

95 I claim:

1. A mounting for a steam lubricator assembly including a lubricant reservoir comprising metal members depending from the lower side of said reservoir, a flat metal member having an area to completely underlie said reservoir and removably supported from the free ends of said first named members, and a clamp means carried at the lower side of the last named member, said clamp means being adapted for engagement about a heated part of a steam power installation whereby heat will be transmitted direct from the said part to said reservoir to maintain the lubricant content of the latter in a usable fluid state at all times.

100 2. A mounting for a steam lubricator assembly including a lubricant reservoir comprising metal leg members depending from the lower side of said reservoir, a metal plate having an area to completely underlie said reservoir and adapted to be adjustably and removably supported from the free ends of said first named members, and a clamp means carried at the lower side of the last named member, said clamp means being adapted for engagement about a heated part of a steam power installation whereby heat will be transmitted direct from the said part to said reservoir to maintain the lubricant content of the latter in a usable fluid state at all times.

105 3. A mounting for a steam lubricator assembly including a lubricant reservoir comprising metal leg members depending in spaced relation from and about the lower
